UNITED STATES PATENT OFFICE

RUDOLF NOSKE, OF SAN FRANCISCO, CALIFORNIA

GUN-SIGHT MOUNTING

Application filed September 19, 1927. Serial No. 220,455.

My invention relates to improvements in mountings for telescope gunsights and the like for firearms.

The present invention is an improvement upon my former invention as disclosed in Letters Patent #1,428,655, granted to me September 12, 1922, and consists in an improved construction and arrangement of parts.

10 The primary object of the present invention is to provide a gunsight mounting of improved construction.

Another object is to provide an improved mounting which will facilitate the adjustment of the sight.

15 A further object is to provide an improved construction affording increased strength and rigidity and which will more efficiently hold the sight against displacement due to recoil and other causes.

20 Another object is to provide an improved device of the character disclosed which will facilitate the construction and assembling of the mounting and which will be more simple and efficient in operation.

I accomplish these and other objects by means of the improved device disclosed in the drawings forming a part of the present application wherein like characters of reference 30 are used to designate similar parts throughout the specification and drawings, and in which,

Fig. 1 is a side elevation of my improved gunsight mounting;

35 Fig. 2 is a plan view of the mounting, the gunsight being omitted from the drawing;

Fig. 3 is a transverse section taken upon the line 3—3 of Fig. 2 in the direction indicated, the figure being drawn upon a larger scale;

40 Fig. 4 is a broken transverse sectional detail showing the construction and arrangement of the adjusting screw, the section being taken upon the line 4—4 of Fig. 2 in the direction indicated;

Fig. 5 is a broken longitudinal section taken upon the line 5—5 of Fig. 2 in the direction indicated.

45 Referring to the drawings, the numeral 1 is used to designate a fixed plate having holes

2 and 3 arranged to receive suitable screws and pins respectively, not shown, whereby the plate may be rigidly secured upon the breech of a rifle, not shown.

The upper edge of the plate 1 is provided with a dovetail 4 arranged to engage a dovetail groove 6 formed in the lower surface of a mounting plate 7. The plate 7 is rigidly locked upon the plate 1 by means of a screw actuated tapered pin 5 as in my former patent above referred to.

The mounting plate 7 is provided with a pivot pin 8 positioned near the forward end thereof. Lugs 9 and 11 are formed upon the forward and rearward ends of the plate 7, said lugs having undercut recesses 12 and 13 respectively formed therein. The rearward end of the plate 7 is split as at 14 for a purpose hereinafter more fully described.

A gunsight mounting member 16 is mounted upon the mounting plate 7, said member 16 consisting of a body portion having a recess 17 formed therein to receive the pivot pin 8. Flanges 18 and 19 are formed upon the ends of the member 16 to be received within the recesses 12 and 13 respectively. Clamps 21 are formed upon the ends of the member 16 to receive a telescope gunsight 22. The clamps 21 consist of lateral extensions shaped to form clamping rings, the extension being split as at 23 adjacent the juncture of the extension with the body of the member 16. The split 23 is preferably arranged radially with respect to the ring portion of the clamp extensions and the base of each extension is made relatively heavy to receive a single clamping screw 24 inserted through an opening 25 in the upper split half of the extension and threaded into the lower base portion whereby the ring may be contracted to rigidly clamp the telescope gunsight 22.

The member 16 is arranged to be pivotally movable upon the pivot pin 8 and is arranged to be pivotally adjusted relative to the plate 7 by means of an adjusting screw 26 threaded into the split rearward end of said plate 7. The screw is provided with a calibrated head 27 receivable into a recess 28 formed in the adjacent side of the plate 7 and arranged to engage the adjacent edge of the member 16.

A collar 29 is threaded onto the opposite end of the screw 26, said collar being arranged to be screwed into tight frictional engagement with the adjacent edge of the member 16 opposite the head 27. The collar is arranged to be received within a recess 31 formed in the adjacent side of the plate 7. The collar is rigidly secured upon the screw 26 by means of an expanding screw 32 tapped into the end of the screw 26 and provided with an inwardly beveled head 33 arranged to expand the end of the screw 26, said screw being split at its end as at 34 to permit said expansion. After threading the adjusting screw 26 through the split end of the plate 7, the split ends are compressed slightly together by means of a screw 35 whereby pressure is exerted in opposite directions by said split portions to take up any backlash from the screw when turned in either direction.

In operation, the fixed plate 1 is rigidly screwed and pinned upon the breech of a rifle and the mounting plate applied and rigidly secured in engagement with the dovetail 4. The sight mounting member is applied by moving the recess 17 onto the pin 8, the member 16 being applied first at substantially right angles to the plate 7 and thereafter turned upon the pivot pin 8 to move the flanges 18 and 19 into locking engagement with the recesses 12 and 13 to lock the member 16 against upward or longitudinal movement. The adjusting screw 26 is applied after the member 16 has been swung into alignment with the plate 7, the screw being threaded into the split ends of the plate 7 as above described until the calibrated head 27 exerts a firm frictional pressure against the adjacent side of the plate 7. The collar 29 is then applied to exert a frictional pressure against the opposite side of the member 16 and rigidly locked by the screw 32. The gunsight 22 is then inserted and secured by the clamping member 16.

In adjusting the sight pivotally upon the plate 7, the adjusting screw is turned by means of the head 27 to advance or recede the screw within the plate 7 as desired. In advancing the screw 26, the head 27, engaging the side of the member 16, causes said member 16 to be pivotally displaced, the degree of displacement being indicated by the number of calibrations upon the head 27 through which the head is turned. The calibrations are arranged to indicate a prescribed displacement at a fixed range. When the screw is receded the collar 29 operates to swing the member 16 in the corresponding direction, the degree of movement being indicated by the calibrated head as before. The pressure exerted in both directions by the split ends of the plate 7 operates to take up all backlash so that there is no lost motion through the threads when the screw is turned in either direction. This point is highly im-

portant to obtain an accurate adjustment of the sight, and to vary the adjustment as required, by means of a single adjusting screw.

While I have illustrated and described the preferred embodiment of my improved construction, the device is of course subject to modification in numerous details without departing from the spirit of the invention. I therefore do not wish to restrict myself to the specific details of construction illustrated and described, but desire to avail myself of all modifications which may fall within the scope of the appended claims.

Having thus described my invention what I claim as new and desire to secure by Letters Patent is:

1. A gun sight mounting comprising a fixed plate arranged to be rigidly secured upon the breech of a rifle; a mounting plate arranged to be rigidly secured upon the fixed plate; a sight mounting member pivotally mounted upon the mounting plate; an adjusting screw threaded into mounting plate and engaging the sight mounting member; a retaining collar mounted upon the screw and engaging the sight mounting member; and means for rigidly securing the collar upon the screw in frictional engagement with the sight mounting member for moving said member when the screw is turned.

2. A gun sight mounting comprising a fixed plate arranged to be rigidly secured upon the breech of a rifle; a mounting plate arranged to be rigidly secured upon the fixed plate; a sight mounting member pivotally mounted upon the mounting plate; an adjusting screw threaded into the mounting plate and provided with a head engaging one side of the sight mounting member; a collar threaded onto the screw upon the end opposite the head and engaging the opposite side of the sight mounting member; and means for rigidly securing the collar upon the screw in frictional engagement with the sight mounting member whereby rotation of the screw in either direction will impart corresponding movement to said member.

3. A gunsight mounting comprising a fixed plate arranged to be rigidly secured upon the breech of a rifle; a mounting plate arranged to be rigidly secured upon the fixed plate; a pivot pin formed upon the forward end of the mounting plate; a lug formed upon the mounting plate forwardly of the pin, said lug having an undercut recess facing said pin; a sight mounting member having a recess arranged to receive the pin and provided with a forwardly disposed flange arranged to be moved into locking engagement with the undercut recess; an adjusting screw threaded into the mounting plate; and means carried by said screw and engaging opposite sides of the sight mounting member for pivotally adjusting said member relative to the mounting plate.

4. A gunsight mounting comprising a fixed plate arranged to be rigidly secured upon the breech of a rifle; a mounting plate arranged to be rigidly secured upon the fixed plate; a pivot pin formed upon the forward end of the mounting plate; a lug formed upon the mounting plate forwardly of the pin, said lug having an undercut recess facing the pin; a sight mounting member having a recess arranged to receive the pin and provided with a forwardly disposed flange arranged to be moved into locking engagement with the undercut recess; an adjusting screw threaded into the mounting plate; a head formed upon one end of the screw to engage one side of the sight mounting member; a collar threaded onto the opposite end of the screw; and means for rigidly securing the collar in frictional engagement with the opposite side of the mounting member.

5. A gunsight mounting comprising a fixed plate arranged to be rigidly secured upon the breech of a rifle; a mounting plate arranged to be rigidly secured upon the fixed plate, said mounting plate having a slit formed at one end thereof; a sight mounting member pivotally mounted upon the mounting plate; an adjusting screw threaded through the split portion of the mounting plate, said split portion being arranged to take up back lash to prevent lost motion when the screw is turned in either direction; and means carried by the screw and engaging opposite sides of the sight mounting member for pivotally moving said member relative to the mounting plate.

6. A gunsight mounting comprising a mounting plate arranged to be rigidly secured upon the breech of a rifle and having a split end; a sight mounting member pivotally mounted upon the mounting plate; a single adjusting screw threaded through the split end portions of the mounting plate; and means carried by said screw for pivotally adjusting the mounting member in either direction relatively to the mounting plate; and means compressing the split end portions of the plate toward each other and against opposite sides of the threads of the screw to take up back lash from the screw and to prevent lost motion when the screw is turned in either direction.

In witness whereof, I hereunto set my signature.

RUDOLF NOSKE.
